ADJUSTABLE LADDER

Harvey C. Wertz, Beaver Falls, Pa.

Application August 6, 1938, Serial No. 223,485

7 Claims. (Cl. 228—63)

The invention relates to ladders for use on sloping or uneven surfaces, and more particularly to a ladder adapted for quick and easy adjustment to accommodate it to varying uneven surfaces.

Prior constructions have included means for adjusting the supporting legs of a ladder, but such constructions have required manipulation of cam levers or locking pins in order to unlock the supporting legs and to lock them in adjusted positions.

Such locking devices are apt to become difficult to operate because of corrosion or lack of lubrication, and do not always function efficiently to positively lock the supporting legs in adjusted position.

Accordingly, it is an object of the present invention to provide an improved ladder construction having adjustable legs for supporting the ladder on uneven surfaces.

Another object is to provide an adjustable ladder having improved means for automatically locking the supporting legs in adjusted positions.

A further object is to provide improved means for positively locking the supporting legs in adjusted positions in such a way that the weight of a person on the ladder increases the locking action.

A still further object is to provide improved means for normally locking the supporting legs of an adjustable ladder in adjusted position, said means being in position to be released by grasping the ladder for adjusting the supporting legs thereof.

These and other objects are accomplished by the improvements comprising the present invention which is illustrated by way of example in the accompanying drawing, described in the specification, and defined in the appended claims.

In general terms the invention may be stated as including a ladder having a step frame with spaced cross bars pivoted thereon and supporting legs pivoted to the ends of the cross bars for relative movement longitudinally of the step frame, one cross bar being movable away from said step frame on its pivotal connection therewith and normally held in engagement with locking bars secured on said step frame.

Referring to the drawing forming part hereof: Figure 1 is a rear perspective view of the improved ladder in adjusted position for resting on an uneven surface;

Fig. 2 is a front elevation of the improved ladder showing an adjusted position in dot-dash lines;

Fig. 3 is a fragmentary side elevation thereof; and

Fig. 4 is a fragmentary sectional view as on line 4—4, Fig. 2.

Similar numerals refer to similar parts throughout the several views of the drawing.

The invention is shown and described as applied to a short step ladder by way of example, but it will be understood that it may be equally well applied to ladders of different sizes and types without departing from the scope of the appended claims.

The improved ladder preferably includes side rails 5 connected at intervals by steps 6 forming a step frame F. The rear supporting leg member 7 may be fork-shaped including two members 8 pivoted as at 9 to the top of the frame F, so that the frame and rear leg member 7 can be folded together when the ladder is not in use.

Preferably a link 10 is pivoted at one end to a bar 11 secured between rear leg members 8, and has an angular flange 12 at its other end for engaging in a slot formed by the U-shaped metal piece 13 on one of the steps 6, for holding the frame F and rear leg 7 in spread apart position. A coil spring 14 may be secured between rear legs 8 at a position spaced below bar 11 over which the flange 12 may be hooked for yieldingly holding the link 10 out of the way when the frame F and rear leg member 7 are folded together.

The means for supporting the step frame F preferably includes adjustable supporting legs 15, located one at each side of the frame and preferably converging toward each other at their upper ends. The legs 15 are pivoted adjacent their lower ends as at 16 to the outer ends of a lower cross bar 17, which is in turn pivoted midway between its ends at 18 to a cross member 19 secured to the side rails 5.

At their upper ends the legs 15 are pivoted by pivots 20 to the outer ends of an upper cross bar 21, and the cross bar 21 has a pivotal connection midway between its ends with a cross member indicated generally at 22 secured to the side rails 5. The cross member 22 may consist of two overlapped pieces 23 and 24 secured to the side rails under one of the steps 6, as shown in Fig. 4, and the pivotal connection of cross bar 21 therewith preferably includes a bolt or pivot pin 25 extending through said pieces 23 and 24 and extending slidably through said cross piece 21, so that the cross bar is movable on the pivot.

An angular bracket 26 is secured on the rear side of cross piece 24, and has a flange 27 spaced

from cross piece 24 in which the rear end of pivot pin 25 is fixed. A spring 28 is provided around pivot pin 25 for yieldingly urging cross bar 21 rearwardly against the flange 27 of bracket 26, as best shown in Fig. 4. A metal sleeve 29 may be provided in cross piece 24 around the spring 28 for shielding the same.

The cross bar 21 is preferably of metal and angular in cross section having a rearwardly extending flange 30. Means for automatically locking the cross bar in adjusted positions preferably includes substantially U-shaped locking bars 31 secured at their ends to the side rails 5, as by screws 32, and having their intermediate portions spaced rearwardly from said side rails.

The cross bar 21 extends between the bars 31 and the side rails, that is, through the openings provided by the locking bars, and the intermediate portions of the locking bars 31 are provided with series of notches or serrations 33 in which the flange 30 of cross bar 21 is adapted to be engaged.

As shown in Fig. 4, the notches 33 are preferably substantially Y-shaped in cross section, so that the flange 30 of cross bar 21 is easily entered and held therein.

When the ladder is supported on an even or flat surface, as indicated in full lines in Fig. 2, the cross bars 17 and 21 are substantially horizontal and the spring 28 yieldingly urges the cross bar 21 rearwardly to hold the flange 30 thereof in engagement with horizontally opposite notches 33.

When it is desired to adjust the supporting legs 15 to rest on an uneven surface without tilting the frame F laterally, the operator grasps the side rails 5 and the adjacent upper ends of the legs 15 in such a way as to squeeze them together. This operation moves the cross bar 21 on its pivot 25 forwardly against cross piece 24, compressing the spring 28 and releasing the flange 30 from engagement with the notches 33.

While the cross bar 21 is held in this position, both the cross bars 21 and 17 may be swung easily about their pivots 25 and 18 respectively, to move one leg upwardly and the other downwardly to the desired adjusted position, such a position being shown in Fig. 1 and in dot-dash lines in Fig. 2. The legs 15 are then released and the spring 28 automatically engages the flange 30 in angularly opposite notches 33 to hold the legs 15 in adjusted position. In other words, as shown in Fig. 1 the flange 30 engages an upper notch of one locking bar 31 and a lower notch of the other locking bar 31.

It is natural to grasp the side rails of a ladder intermediate their top and bottom ends when lifting, transporting or adjusting the ladder. In the present improved adjustable ladder, the cross bar 21 is released from engagement with the locking bars 31 for adjusting the ladder by merely grasping the side rails at the usual places in the accustomed manner and at the same time squeezing the upper ends of the adjustable legs 15 and the side rails together. Accordingly, the ladder 65 may always be held with both hands on the side rails even though the supporting legs are being adjusted.

Obviously, the weight of a person on the ladder will increase the frictional locking engagement between the locking bars 31 and the cross bar 21 so as to more securely hold the legs in any adjusted position within the limits of the series of notches 33.

The improved ladder is simple, compact and inexpensive to make, and is easily manipulated

and adjusted. When the operator releases his hold on the side rails of the ladder the supporting legs are automatically locked in position.

It should be understood that various modifications in details of construction and arrangement 5 may be made in the present improved ladder as shown and described, without departing from the scope of the appended claims.

I claim:

1. An adjustable ladder including a step frame, 10 cross bars spaced longitudinally of said step frame and pivotally connected thereto intermediate their ends, supporting legs at the sides of said step frame pivoted to the ends of the cross bars, one of said cross bars being movable away from said step frame on its pivotal connection therewith, a locking bar secured on said step frame adjacent said movable cross bar, and means yieldingly urging said movable cross bar into engagement with said locking bar.

2. An adjustable ladder including a step frame, cross bars spaced longitudinally of said step frame and pivotally connected thereto intermediate their ends, supporting legs at the sides of said step frame pivoted to the ends of the cross bars, 25 one of said cross bars being movable away from said step frame on its pivotal connection therewith, a locking bar having notches secured on said step frame adjacent said movable cross bar, and spring means yieldingly urging said movable cross bar into engagement with said locking bar notches.

3. An adjustable ladder including a step frame having side rails, spaced upper and lower cross bars pivotally connected intermediate their ends 35 on said step frame, supporting legs at the sides of said step frame pivoted to the ends of said cross bars, the upper cross bar being movable on its pivotal connection with said frame in a direction toward and away from said frame, serrated locking bars secured on said step frame side bars, and spring means yieldingly urging said movable cross bar into engagement with the serrations of said locking bars.

4. In an adjustable ladder having a step frame, 45 spaced cross bars pivoted on said frame, and supporting legs pivoted to said cross bars, means for locking said legs in adjusted position, said means including a locking bar secured to the frame, and a spring urging one of said cross bars away from 50 said frame and into locking engagement with said locking bar.

5. An adjustable ladder including a step frame having side rails, U-shaped locking bars having their ends secured to said side rails and including 55 notched portions spaced rearwardly thereof, upper and lower cross bars pivotally connected intermediate their ends on said step frame, said upper cross bar extending between said side rails and said locking bar notched portions, spring 60 means urging said upper cross bar into locking engagement with said locking bar notched portions, and supporting legs pivoted to the ends of said cross bars at the sides of said step frame.

6. An adjustable ladder including a step frame 65 having side rails, U-shaped locking bars having their ends secured to said side rails and including notched portions spaced rearwardly thereof, upper and lower cross bars pivotally connected intermediate their ends on said step frame, said upper cross bar extending between said side rails and said locking bar notched portions and having 70 a rearwardly directed flange, spring means at the pivotal connection between the upper cross bar and urging said cross bar rearwardly to engage 75

said flange with the notched portions of said locking bars, and supporting legs pivoted to the ends of said cross bars at the sides of said step frame.

7. An adjustable ladder including a step frame having side rails, a lower cross bar pivoted intermediate its ends on said step frame, a pivot pin on said step frame spaced upwardly from said lower cross bar, an upper cross bar mounted intermedi-

ate its ends on said pivot pin and slidably axially thereof, a locking bar on said step frame, a spring on said pivot pin between said step frame and said upper cross bar for urging said cross bar into engagement with said locking bar, and supporting legs pivoted to the ends of said cross bars at the sides of said step frame. 5

HARVEY C. WERTZ.
